UNITED STATES PATENT OFFICE.

EDWIN W. RICE, JR., OF SCHENECTADY, NEW YORK, ASSIGNOR TO GENERAL ELECTRIC COMPANY, A CORPORATION OF NEW YORK.

TURBINE-BUCKET CONSTRUCTION.

980,562.

Specification of Letters Patent. Patented Jan. 3, 1911.

Application filed June 28, 1909. Serial No. 504,639.

To all whom it may concern:

Be it known that I, EDWIN W. RICE, Jr., a citizen of the United States, residing at Schenectady, county of Schenectady, State 5 of New York, have invented certain new and useful Improvements in Turbine-Bucket Construction, of which the following is a specification.

The present invention relates to turbine 10 bucket construction, and has for its object to provide an improved means for securing the cover or shroud to the free ends of the buckets.

For a consideration of what I believe to 15 be novel and my invention, attention is directed to the accompanying description and claims appended thereto.

In the accompanying drawing which is 20 illustrative of my invention, Figure 1 is a view in side elevation of a portion of a row of buckets either for a rotor or stator; Fig. 2 is a plan view of a bucket; Fig. 3 is a sectional view of a bucket showing the cover or shroud in place; Fig. 4 is a detail view 25 showing the cover in section and a bucket in dotted lines; Fig. 5 shows a slight modification wherein the cover or shroud is secured by two means instead of one; Fig. 6 is a side view of a cover or shroud and Fig. 7 is a 30 bottom view of the shroud or cover.

My invention is applicable to impulse and reaction turbines, and to a combination of both types, and this whether the buckets, blades or vanes are carried by disk-like 35 wheels or drums. It is also applicable to stator as well as rotor buckets.

1 indicates the carrier or support for the buckets which may be stationary or rotary. It may be a disk, wheel, drum or casing or a 40 part which is secured thereto. Mounted on the carrier are buckets or vanes 2 which may extend radially or axially depending upon the direction of flow of the steam or other motive fluid. The buckets or vanes may be 45 secured at their roots by any suitable means. Mounted on the buckets or vanes is a cover or shroud 3 that is made in one or more pieces or sections, usually in a number of 50 relatively short lengths for convenience in manufacturing and assembling, especially where the buckets or vanes have a slanting top or end to provide for an enlargement of the spaces or working passages between said buckets or vanes. The cover is made of 55 some good tough metal and is relatively thin

in order to make it as light as possible. The under side of the cover or shroud is provided with projections 4 usually one for each bucket. These projections may be formed in a variety of ways and for the purpose of 60 strength are made integral with said cover but under certain conditions where the centrifugal stresses are moderate they may be separately made and affixed to the cover. In either event they will form a part of the 65 cover or shroud as distinguished from the buckets. Assuming that they are to be formed integral, a convenient method of manufacture is as follows: The cover is rolled or otherwise formed to the desired 70 shape and size and on the under side is formed a ridge 5 of suitable depth and width to form the finished projection 4. The portion of the ridge 5 between the projections may then be removed by a milling 75 or other machine operation. I prefer to remove this metal in order to avoid forming a resistance or obstruction in the bucket space. The tops or free ends of the buckets 80 are provided with grooves or recesses of such shape that when the metal forming the projections is upset, expanded or caused to flow therein under pressure, the projections will fill said grooves or recesses and firmly unite the cover and the buckets. As an example 85

I may advantageously use dovetail slots or grooves 6. The under surface of each projection may be so shaped or beveled that when forced against the bottom wall of the groove it will tend to expand. Such an arrangement is shown at 7, Fig. 4. This shape is or may be given to the entire ridge when it is found desirable to obviate an additional machine operation.

In assembling, the buckets are first mounted in place on the carrier, or for that matter they may be formed integral therewith. The cover or shroud is then mounted in position on the buckets with the projections registering with the dovetail grooves, slots, or 95 recesses. Pressure is then applied to the cover directly over the projections 4 which causes their lower ends to expand and fill said grooves or slots. This pressure may be applied in a variety of ways depending upon the arrangement and character of the buckets. It may be done by a pneumatic hammer, or by pressure from a ram or other agency. Where the buckets are relatively 100 thin they may be supported by clamps or 105

other means to keep them from bending during the upsetting or expanding operation on the projections.

Where the buckets are relatively thin and long as in the low pressure stages I may employ two projections for each bucket as shown in Fig. 5.

In some cases, especially where the buckets have a tendency to move from their proper positions in the plane of the row of buckets due to the force exerted by the motive fluid thereon, or otherwise, additional means are provided to prevent such tendency. As an illustration of this feature of my invention the projections are provided with extensions or pins 8 that enter correspondingly-shaped holes 9 in the buckets. When the projections 4 are inserted in the grooves 6 preparatory to expanding them the pins will enter the holes 9 and the proper relation of the parts will be preserved not only during the expanding operation but when the machine is in service.

In accordance with the provisions of the patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:—

1. In a turbine, the combination of a support, buckets mounted thereon and arranged in a row, said buckets having open-ended slots in their free ends, a cover or shroud for the free ends of the buckets, means carried by the cover and engaging the slots for uniting said cover with the buckets, and devices for preventing the buckets from moving relative to the cover in the plane of the row.

2. In a turbine, the combination of a support, buckets mounted thereon that have open-ended dovetail grooves in their free ends, a cover for the buckets having integral projections that enter the grooves in the

buckets and are expanded therein to hold the cover in place, and devices for preventing the walls of the bucket grooves and the projections from being disengaged. 50

3. In combination, a plurality of turbine buckets having recessed outer ends, a support for the buckets, a cover or shroud for the free ends of the buckets, and projections on the under side of said cover which enter the recesses, the end of each projection being beveled from the edges toward its center to facilitate expanding when pressure is 55 applied thereto. 60

4. In a turbine, the combination of a support, buckets mounted thereon that have open-ended dovetail grooves in their free ends, there being holes extending into the 65 bodies of the buckets from the bottom of the grooves, a cover for the buckets having integral projections that enter said grooves and are expanded therein to hold the cover in place, and extensions on the projections 70 that enter said holes to prevent the walls of the bucket grooves and the projections from being disengaged. 70

5. In combination, a support, a bucket mounted thereon that has an open-ended 75 groove in its free end and a hole extending into the body of the bucket from the bottom of the groove, a bucket cover having a projection which engages the groove and is secured therein, and an extension on the projection that engages said hole. 80

6. In combination, a support, a bucket mounted thereon, a cover for the bucket, and means for securing the cover to the bucket comprising a projection on one of 85 said members engaging an open-ended slot in the free end of the other and an extension on the projection that enters a hole extending from the bottom of the slot.

In witness whereof, I have hereunto set 90 my hand this 26th day of June, 1909.

EDWIN W. RICE, JR.
